UNITED STATES PATENT OFFICE.

OTTO A. SCHROEDER, OF GREEN BAY, WISCONSIN.

SICK-BED TRAY.

1,274,609.

Specification of Letters Patent.

Patented Aug. 6, 1918.

Application filed August 27, 1917. Serial No. 188,452.

To all whom it may concern:

Be it known that I, OTTO A. SCHROEDER, a citizen of the United States, residing at Green Bay, in the county of Brown, State 5 of Wisconsin, have invented certain new and useful Improvements in Sick-Bed Trays; and I do hereby declare the following to be a full, clear, and exact description of the invention, such as will enable others skilled in 10 the art to which it appertains to make and use the same.

This invention relates to bedside trays or tables.

The object of the invention is to provide a 15 simple and practical tray for sick-beds, which may be directly mounted upon the bed post, in such a manner as to be adjustable over or away from the bed at the will of the occupant.

20 With the above objects in view, and such others relating to the details of construction, as may hereinafter appear, my invention will now be fully set forth and described, reference being had to the accompanying 25 drawings.

In the drawings:—

Figure 1 is an elevation showing the device mounted upon a bed post,

Fig. 2 is a plan view thereof,

30 Fig. 3 is an enlarged sectional detail view taken on the line 3—3 of Fig. 1.

Fig. 4 is a further enlarged sectional detail view, and

Fig. 5 is a detail view of a modified form 35 of the invention.

Referring more particularly to the drawings, 1 represents a bed post of the type used in the construction of metal beds. Adapted to be mounted upon the post 1 is a pair of 40 clamps 2 which are connected in a fixed spaced relation by means of a connecting rod 3. Each of the clamps 2 consists of a pair of semi-circular clamp members which are hinged to a bracket member 4 and are 45 adapted to be locked together about the post 1 by means of the clamp screw 5. The connecting rod 3 is passed through the bracket members 4, and while allowing these members to swing therearound, so as to properly 50 position the clamps 2, it holds them in their fixed spaced relation so as to properly locate the lower members 6 of a pair of knuckle joints, which are carried upon the free extremities of the bracket members 4. 55 Surmounting the lower members 6 are the members 7 which complete the knuckle

joints, the members 7 being carried upon the free ends of the shanks 8 which extend outwardly from a standard 9. The standard 9 is therefore adapted to be swung in an arc around the bed post 1, and in order to position the standard in any desired position of adjustment, a resilient clamp is carried by the knuckle joints, said clamp including a bolt-like member 11 which is passed through 60 the members 6 and 7 centrally thereof and the head of this bolt 11 forms an abutment for one end of a coiled tension spring 13, which has its opposite end working against the member 7. Threaded on the bolt 11 at 65 its lower end is a winged nut 13' to vary the gripping action of the members 6 and 7 constituting the knuckle joints.

Extending from the lower end of the standard 9 is a horizontal rail 15 which is 70 braced by means of a pair of brace rods 16 which extend from the standard 9 to points along the length of the rail 15. Also, extending to one side from the rail 15 is a pair of arms 17 whose extremities are connected by a second rail 18. The rails 15 and 18 provide a support for a tray or table 19. Thus, the tray or table 19, upon its lower face, is provided with a pair of open rings 80 20 which are slidable upon the rail 18, and the tray is furthermore provided with a rearward projection 21, which when the table rests in a horizontal position bears below the rearmost rail 15 thereby securely supporting the tray. Obviously, it is necessary for the 90 rearmost rail 15 to stand at a higher level than the forward rail 18, so that the tray or table 19 may stand in horizontal position. When it is necessary to dispose of the table 19, it may be swung upwardly upon the rail 95 18, until its upper face bears against the top brace rod 16.

Obviously, in the use of the device which has been described, the standard 9, with the rails 15 and 18 may be swung into alinement 100 with the bed rails, or the framing may be swung back against the wall, that is away from the bedside. Then, the tray 19 may be positioned longitudinally of the bed, so as to suit the needs of the occupant, by sliding 105 it upon the rails 15 and 18.

As a modification of the mechanism above described, arms 17' may be extended in opposite directions from the rail 15, and connected by rails 18' thereby making it possible to mount the tray 19 upon either side of the framing, so that the device may be used 110

upon the right or left hand side of the bed. Since the rings 20 are open, to permit the tray 19 to be readily lifted from the rail 18, it is but the work of a moment to shift the tray 19 from one side of the framing to the other.

It will be apparent from the foregoing description that I have provided a very simple and practical bedside tray for use in hospitals or sick rooms, which may be quickly mounted or taken down, and which, where it is periodically needed at infrequent intervals may be swung to one side of the bed without taking up an undue amount of space.

What I claim as my invention is:—

A device of the character described comprising spaced clamping means adapted to

embrace the post of a bed, a connecting rod joining the spaced means, a vertical frame 20 having a lower horizontal bar and an offset right angular extension consisting of a horizontal rail spaced at one side of said bar and below the plane thereof, a shelf section slideable on said rail and disposed beneath the 25 bar, resilient clips on the shelf section and detachably engaging the rail, and hinged clutch connections between the frame and said first named means.

In testimony whereof I affix my signature 30 in the presence of two witnesses.

OTTO A. SCHROEDER.
